FLOOR MAT

James R. Caldwell, Wooster, Ohio, assignor to
The Wooster Rubber Company, Wooster, Ohio

Application April 18, 1949, Serial No. 2,093

Term of patent 14 years

(Cl. D9—6)

To all whom it may concern:

Be it known that I, James R. Caldwell, a citizen of the United States, residing at Wooster, in the county of Wayne and State of Ohio, have invented a new, original, and ornamental Design for a Floor Mat, of which the following is a specification, reference being had to the accompanying drawing, forming part thereof, wherein:

I claim:

The ornamental design for a floor mat, substantially as shown.

JAMES R. CALDWELL.
